UNITED STATES PATENT OFFICE.

CHARLES H. WARREN, OF ATLANTA, GEORGIA, ASSIGNEE TO DRAPER CORPORATION,
OF HOPEDALE, MASSACHUSETTS, A CORPORATION OF MAINE.

FILLING-END-WITHDRAWING MEANS FOR WEFT-REPLENISHING LOOMS.

1,265,558.

Specification of Letters Patent. Patented May 7, 1918.

Application filed September 17, 1917. Serial No. 191,701.

To all whom it may concern:

Be it known that I, CHARLES H. WARREN, a citizen of the United States, residing at Atlanta, county of Fulton, State of Georgia, have invented an Improvement in Filling-End-Withdrawing Means for Weft-Replenishing Looms, of which the following description, in connection with the accompanying drawing, is a specification, like characters on the drawing representing like parts.

This invention relates to weft replenishing looms preferably of the automatic type and its object is to provide means for engaging and withdrawing the trailing end of the abandoned filling carrier after its discharge from the shuttle in the operation of replenishment so that it will not be caught and carried by the shuttle or the fresh filling carrier into the cloth upon the succeeding pick.

20 This object is secured in the present invention by means mounted upon the lay and operated by the picker and acting when struck by the picker to engage and withdraw the trailing end of the filling from the shuttle.

These and other objects of the invention will appear more fully from the accompanying description and drawings and will be particularly pointed out in the claims.

30 In the drawings,

Figure 1 is a front elevation of so much of the transfer end of an automatic weft replenishing loom of the Northrop type as is necessary to a disclosure of the present invention with a preferred form of the said invention embodied therein;

Fig. 2 is a top plan view partially broken away and partially in horizontal cross section of a portion of the construction illustrated in Fig. 1.

The present invention is not concerned with the particular construction or operation of the general features of the loom to which it is applied. For convenience of illustration the invention is shown in the preferred form selected as embodied in an automatic filling replenishing loom of the well known Northrop type.

In this type of loom the frame or loom 50 side 1 supports at the transfer end of the loom a hopper stand 2 upon which is mounted a rotary hopper 3 carrying the supply of fresh filling carriers 4. The lay 5 carries at the transfer end the shuttle box 6 and the lay and shuttle box are provided with a vertical opening 7 therethrough to permit the

downward discharge of an abandoned filling carrier when the shuttle is boxed at the transfer end of the loom.

The usual transerrer 8 pivotally mounted on the hopper stand at 9 is actuated upon the call for filling replenishment to force a fresh filling carrier, in this case a bobbin, from the hopper 3 into the shuttle 10 therebeneath on the lay and thereby discharge the abandoned or exhausted filling carrier or bobbin from the shuttle down through the opening 7.

The shuttle is picked back and forth on the lay by the usual pickers one of which is shown at 11. This picker projects vertically through the opening 7 and operates therein. It is shown in Fig. 1 at its extreme right hand position when the shuttle is boxed. It swings from this position to the left to pick the shuttle across the lay.

75 The end of the filling extending or trailing from the abandoned filling carrier through the eye of the shuttle is, in feeler looms, usually severed by suitable mechanism adjacent the nose of the shuttle and this severed end must be drawn back through the eye of the shuttle and clear of the shuttle or in other words it must be withdrawn from the shuttle or it is liable to be caught by the shuttle or by the fresh filling carrier and 80 dragged back into the shed and woven into the cloth causing an imperfection.

In this invention means are provided mounted upon the lay and preferably actuated by the picker to engage and withdraw 90 from the shuttle the trailing end of the discharged filling carrier and thus prevent it from being dragged back into the shed by the shuttle or the fresh filling carrier.

The preferred form of mechanism illustrated for this purpose is shown as a device comprising a fixed member mounted on the lay in front of the opening 7 and a movable member mounted on the lay and projecting across the said opening and acting when 100 struck by the picker to engage the trailing end of filling and jerk it across and about the fixed member thus withdrawing the trailing end from the shuttle.

105 The fixed member is shown as a finger 12 secured at its right hand end by the bolt 13 to the lay and extending along and in front of the opening 7. The movable member is shown as a wire loop 14 secured at its ends to a stud 15 and by which it is conveniently 110 pivoted in the finger 12 and in a bracket 16 secured by the bolt 13 to the lay and de-

pending beneath the finger. A helical spring 17 is coiled about the pivot 15 and secured at one end to the loop 14 and at the other end to the bracket 16 and acts to swing the loop or movable member across the opening 7 into contact with the rear wall thereof as shown at full lines in Fig. 2. When the picker 11 moves to the left it comes immediately into contact with the loop 14 and swings it with a quick jerk across the opening causing it to straddle the finger 12 and move into the position indicated in dotted lines in Fig. 2.

The operation of the invention will now 15 be apparent. When replenishment takes place and the exhausted and abandoned filling carrier is discharged from the shuttle 10 it passes down through the opening 7 and falls into a receptacle usually provided beneath the loom. The trailing end of the 20 filling if not withdrawn from the shuttle by the filling carrier itself extends back through the eye of the shuttle and between the shuttle and the box. From the eye the end extends 25 down through the opening 7 in front of the loop 14. If it remains in this position the picker 11 immediately it begins its action comes into contact with the loop 14 and with a quick jerk swings the loop into 30 the position shown in dotted lines in Fig. 2 thus causing the loop to engage the trailing end of filling and withdraw it by a quick jerk through the eye of the shuttle and from between the shuttle and the box 35 thus freeing it entirely from the shuttle.

Having fully described my invention, what I claim as new and desire to secure by Letters Patent is:

1. In a weft replenishing loom, a lay provided with a shuttle box and having an opening therethrough to permit the discharge of the abandoned filling carrier and to permit the movement of the picker, a picker, and means movably mounted on the lay and operated by the picker to engage and withdraw from the shuttle the trailing end of the discharged filling carrier.

2. In a weft replenishing loom, a lay provided with a shuttle box and having an opening therethrough to permit the discharge of the abandoned filling carrier and to permit the movement of the picker, a picker, and a device comprising a member movably mounted on the lay and projecting

across said opening and acting when struck by the picker to engage and withdraw from the shuttle the trailing end of the discharged filling carrier.

3. In a weft replenishing loom, a lay provided with a shuttle box and having an opening therethrough to permit the discharge of the abandoned filling carrier, a device comprising a member movably mounted on the lay and projecting across said opening, and means acting upon the discharge of the filling carrier to swing said movable member into engagement with the trailing end to withdraw said trailing end from the shuttle.

4. In a weft replenishing loom, a lay provided with a shuttle box and having an opening therethrough to permit the discharge of the abandoned filling carrier, a device mounted on the lay and comprising a fixed member and a movable member, and means acting upon the discharge of the filling carrier to swing said movable member into engagement with the trailing end and carry it against said fixed member and thus withdraw it from the shuttle.

5. In a weft replenishing loom, a lay provided with a shuttle box and having an opening therethrough to permit the discharge of the abandoned filling carrier, a device mounted on the lay comprising a fixed finger and a loop member movable to straddle said finger, and means acting upon the discharge of the filling carrier to swing said loop member into engagement with the trailing end and carry it about said fixed finger and thus withdraw it from the shuttle.

6. In a weft replenishing loom, a lay provided with a shuttle box and having an opening therethrough to permit the discharge of the abandoned filling carrier and to permit the movement of the picker, a picker, a device comprising a member fixed with respect to the lay and a member movable with respect to the lay across said opening, the said movable member acting when struck by the picker to swing across said opening into engagement with the trailing end and carry it against said fixed member and thus withdraw the end from the shuttle.

In testimony whereof, I have signed my name to this specification.

CHARLES H. WARREN.
